UNITED STATES PATENT OFFICE.

MORRIS J. CHAIKIN, OF DETROIT, MICHIGAN.

TIRE-PUMP.

1,388,326.

Specification of Letters Patent. Patented Aug. 23, 1921.

Application filed June 5, 1920. Serial No. 386,861.

To all whom it may concern:

Be it known that I, MORRIS J. CHAIKIN, a citizen of the Dominion of Canada, residing at Detroit, in the county of Wayne and State of Michigan, have invented a new and useful Tire-Pump, of which the following is a specification.

This invention relates to tire pumps, and it is the object of the invention to provide a tire pump manually actuatable by turning of the crank, and to provide for adjustment of the actuating mechanism from its normal position of use to a stored position, securing increased compactness and permitting disposal of the pump within the tool box of a motor vehicle.

In attaining this object the invention contemplates the arrangement of a pair of standards, one at each side of the cylinder, which standards engage the heads of the cylinder and are employed to clamp said heads upon the body of the cylinder, the standards being extended above the cylinder and functioning additionally to provide a mounting upon which a crank and gear drive mechanism for the pump is adjustable from an elevated position of use to a stored position comparatively close to the cylinder.

A preferred embodiment of the invention is hereinafter described and is illustrated in the accompanying drawings, wherein:

Figure 1 is a front view of the improved pump, showing the actuating mechanism in position of use.

Fig. 2 is a similar view with said mechanism in stored position.

Fig. 3 is a sectional elevation of the invention, taken on line 3—3 of Fig. 1.

Fig. 4 is a cross-section on line 4—4 of Fig. 1, showing the engagement of the cross-head of the pump with the standards thereof.

Fig. 5 is a cross-section on line 5—5 of Fig. 1, showing the adjustable head which carries most of the actuating mechanism.

Fig. 6 is a vertical sectional view, showing the mounting of said adjustable head upon the upper portions of said standard, and disclosing the gearing carried by said head.

In these views the reference character 1 designates the body of the pump cylinder, and 2 and 3 the upper and lower heads of said cylinder. Cylindrical rods 4, one of which is arranged at each side of the cylinder, are engaged with diametrically opposed lugs 5 upon the cylinder heads, and are fur-

ther extended above the cylinder to provide standards for carrying an actuating mechanism for the pump. To adapt the rods 4 to clamp the heads 2 and 3 upon the cylinder, 60 said rods are formed with heads 6, forming abutments for the upper cylinder head 2, the lower cylinder head being engaged by nuts 7 threaded upon the corresponding ends of said rods. Thus, by tightening up the nuts 65 7 the two cylinder heads are clamped simultaneously upon the body 1, as firmly as may be necessary. 8 and 9 designate respectively the piston and piston rod of the pump, and 10 an air outlet nipple engaging the lower 70 cylinder head. Upon its upper end said piston rod rigidly carries a cross-head 11, the ends of which are bifurcated to form mountings for a pair of grooved rollers 12 which respectively engage the rods 4. A pitman 13 75 is connected at one end to the cross-head 11 and at its other to a crank 14 fast upon a stud shaft 15. Said shaft is adapted to be driven through a pair of spur gears 16 from an overlying stub shaft 17 upon which the 80 hand crank 18 is mounted fast. The shafts 15 and 17 are journaled in a head formed by a pair of spaced plates 19, vertically grooved at their ends, as indicated at 20, to engage the rods 4, and clamped in opposed relation 85 upon said rods by a pair of wing-headed screws 21. The central portions of said plates are spaced apart to form a chamber 22 within which the gears 16 are arranged. It is preferred to form one of said plates 90 with an integral upwardly extending arm 23, upon which a handle 24 is provided, and to form the rods 4 with similar heads 25 at their upper ends.

Discussing now the operation and advantages of the described construction, it is to be first observed that the clamping screws 21 may very readily be loosened to permit the head 19 to be shifted from one to the other of its two positions, respectively illustrated in Figs. 1 and 2. When in its raised position said head abuts the heads 25, the latter thus determining the proper position of use for the actuating mechanism. Grasping the stationary handle 24 with one hand, the operator turns the crank 18 with the other, thus transmitting rotation through the gears 16 to the crank arm 14, and effecting reciprocation of the piston 8 through the pitman 13 and piston rod 9. The cross-head 11, through its engagement with the rods 4, safeguards the piston rod against

bending stresses and friction between the cross-head and rods is minimized by provision of the rollers 12. When not in use the head 19, after loosening of the clamping screws 21, may be lowered as shown in Fig. 2, the pitman 13 and crank arm 14 assuming a vertical position and overlapping relation, and the arm 23 assuming a position between the upper portions of the rods 4, so that the height over all is no greater than that of said rods. Thus, the pump acquires, in the stored position of its actuating mechanism, a compactness such as will readily permit it to be carried in an ordinary motor vehicle tool box.

What I claim is:

1. A tire pump comprising a cylinder, a standard carried by and projecting upwardly from said cylinder, a piston within the cylinder, a piston rod secured to said piston, a pitman engaging said piston rod, a crank arm engaging said pitman, actuating means for the crank-arm, and a mounting for said actuating means and crank-arm carried by said standard and adjustable from a position of use adjacent the top thereof to a lower stored position.

2. A tire pump comprising a cylinder, a standard carried by and projecting upwardly from said cylinder, a piston within the cylinder, a piston rod secured to said piston, a pitman engaging said piston rod, a crank-arm engaging said pitman, actuating means for the crank-arm, and a mounting for said actuating means and crank-arm carried by said standard and adjustable from a position of use adjacent the top thereof to a lower stored position, said pitman and crank-arm assuming a vertical position and an overlapping relation in said stored position.

3. A tire pump comprising a cylinder, a standard carried by and projecting upwardly from said cylinder, a piston within the cylinder, a piston rod secured to said piston, a pitman engaging said piston rod, a crank-arm engaging said pitman, actuating means for the crank-arm, a mounting for said actuating means and crank-arm carried by said standard and adjustable from a

position of use adjacent the top thereof to a lower stored position, an arm extending upwardly from said mounting, and a handle secured to said arm.

4. A tire pump comprising a cylinder, a piston within said cylinder, a pair of spaced standards carried by and projecting upwardly from the cylinder, a cross-head engaging said standards, a piston rod attached to said piston and carrying said cross-head, a pitman engaging said cross-head, a crank-arm engaging said pitman, actuating means for said crank-arm, and a mounting for said actuating means and crank-arm clamped upon said standards and adjustable from a position of use adjacent the tops of the standards to a lower stored position.

5. A tire pump comprising a cylinder, a piston within said cylinder, a pair of spaced standards carried by and projecting upwardly from the cylinder, a cross-head engaging said standards, a piston rod attached to said piston and carrying said cross-head, a pitman engaging said cross-head, a crank-arm engaging said pitman, an actuating crank, a gearing for rotating said crank-arm from said crank, and a pair of plates oppositely clamped upon said standards, and spaced to provide a housing for said gears, said plates forming a mounting for the crank, crank-arm, and gears, and being adjustable from a position of use adjacent the tops of said standards to a lowered stored position.

6. A tire pump comprising a cylinder including upper and lower cylinder heads, a pair of standards arranged one at each side of the cylinder and projecting thereabove, abutments upon said standards engaging the upper cylinder head, nuts engaging the lower ends of the standards and bearing upon the lower cylinder head, a piston within said cylinder, and actuating mechanism for said piston adjustable from a position of use adjacent the tops of the standards to a lower stored position.

In testimony whereof I sign this specification.

MORRIS J. CHAIKIN.
